corporation of Pennsylvania

Application June 20, 1944, Serial No. 541,189

3 Claims. (Cl. 153—48)

1

The invention relates to improvements in stretch bending; that is, in curving profiles by stretching or simultaneously bending and stretching a workpiece over a die. The invention relates also to equipment for carrying out the new process.

The outstanding object of the invention is the avoidance of over-stretching on the convex side of the curvatures which the hitherto customary procedure necessitated.

The object of the invention is achieved mainly by exerting during the forming operation a greater stretching force on the concavely curved side of the workpiece than on the convex side thereof.

The invention and its objects and advantages will be more fully understood from the attached drawing and the following description of an embodiment:

In the drawing,

Figure 1 is a diagrammatic side elevation, certain parts in section and others broken away, of a stretch bending machine equipped for carrying out the invention;

Figure 2 is a section through the bending die and a workpiece along line 2—2 of Figure 1, but on a larger scale;

Figure 3 is a fragmentary side elevation of the workpiece diagrammatically showing the stresses applied to the workpiece by simple bending, by customary stretching and bending, and by the stretch bending according to the invention;

Figure 4 is a side elevation of one of the vises shown in Figure 1 on a larger scale, partly in section; and

Fig. 5 is a fragmentary section along line 5—5 and on the scale of Figure 4; and

Figure 6 is a fragmentary section along line 6—6 of Figure 5.

The machine illustrated in Figure 1 has a base plate 10 supporting a hydraulic cylinder 11 and integrally connected to two pairs of vertical webs 12. A piston 13 in the cylinder 11 has a piston rod 14 the upper end of which carries a plate 15 adapted for the support of a forming die 16.

Between each pair of webs 12 is arranged a vise 17 provided with laterally extending pins 18 which are rotatably supported in corresponding holes or bearings of the webs 12. The vises 17 are adapted for firmly gripping the ends of a workpiece 19 by means of jaws which are not shown; the jaws and the screws or bolts 20 for tightening them may be of any appropriate construction.

While the machine is merely diagrammatically shown, because as a whole it does not constitute

2

a feature of the invention, it may well be of more elaborate construction.

The machine is used as follows:

A straight or pre-bent workpiece 19 has its ends secured in the vises 17 so that it extends over the correspondingly shaped surface of the die 16. Thereupon, pressure fluid is admitted through the pipe 21 to the cylinder 11 whereby the piston 13 with its rod 14, and plate 15 with the die 16 are forced upwardly so that the workpiece 19 is stretched beyond its elastic limit and retains, after removal from the machine, the exact form given to the working surface of the die. The rotatable attachment of the vises 17 permits the adjustment of the same in the tangential direction of the end portions of the die 16, as illustrated in Figure 1.

With a customary machine, the neutral axis intersecting line 22 at the end of the workpiece would be in the plane of the axis about which the adjacent vise swings. Consequently, the tension exerted on the workpiece by the movement of the die is about equally distributed over the cross section of the workpiece. If this equal stretching is superimposed on the stresses indicated by the lines 23 caused by the mere bending of the workpiece, the stresses result which are diagrammatically indicated by the lines 24. So as to obtain a permanent setting by stretching, it is obviously necessary to stretch the workpiece to such an extent that it is stretched also on the concave side at 25 beyond the elastic limit, with the result that the stretch on the convex side at 26 is substantially greater than required for attaining a permanent setting in this region. This condition may lead to an objectionable over-stressing on the convex side, over-stressing to such an extent that it impairs the strength of the workpiece.

The aforesaid shortcomings of the known procedures are overcome or alleviated by superimposing on the bending stresses a stretching force which is greater on the concave side of the workpiece than on the convex side thereof. The resultant stress diagram is indicated by the lines 27. It will be noted that the imaginary neutral axis, intersecting line 28, is moved far inwardly in the stress diagram according to the invention, as compared with the imaginary neutral axis on line 29 of the stress diagram of the ordinary stretch bending procedure.

It will be understood that the lines 22, 28 and 29 represent the loci of the neutral axes for all points along the length of the workpiece.

The lines 23 may be called "bending stress

lines" and the lines 24 and 27 "elongation-stress lines." Note that the angle between the neutral plane 22 and the lines 23 and 24, respectively, are about equal, whereas the angles between said plane 22 and the elongation stress lines 27 is closer to 90° than the angles between the bending stress lines 23 and said plane 22.

The desired distribution or equalization of the stresses may be obtained by arranging the swivel axis 30 for the vises eccentrically with respect to the neutral plane 22 of the workpiece toward the concave side of the latter. The proper eccentricity has to be determined for each material, cross section and form.

The vise illustrated in the drawing has its pins 18 respectively adjustable transversely to the direction of the end of the workpiece. This adjustment is achieved by providing the pins 18 on a block 31 extending through the hollow interior 32 of the vise body and slidably guided in slots 33 communicating with said interior and the outside. The block 31 is screw threaded for receiving a threaded spindle 34 which has its ends rotatably supported respectively in plate 35 secured to one wall and in the opposite wall of the body of the vise 17. At least one of the ends of the spindle 34 has a square head 36 permitting the turning of the spindle so as to transversely move and adjust the block 31 together with its pins 18.

The eccentric arrangement of the axes 30 of the vises relative to the neutral plane 22 of the workpiece obviously causes the exertion of greater stresses on that side of the plane 22 on which the axes 30 are located.

The invention is not restricted to the illustrated embodiment but many of the described features may be modified or substituted without departing from the spirit of the invention. All modifications and adaptations of the invention are intended to be covered by the claims.

What is claimed is:

1. In a method of forming a workpiece by gripping its ends and bending and stretching it over a die having a curved working surface, the feature of exerting at the ends of the workpiece a greater stretching force on the concave side than on the convex side thereof so as to equalize the resultant stretch exerted on the workpiece by the stretching proper and by the bending.
- 10 2. Vise for stretch bending machines provided with means for clamping it to the end of a workpiece and means for attaching it to the machine freely swingable about an axis transversely offset relative to the neutral plane of the workpiece.
- 15 3. Vise for stretcher presses comprising a journal for securing the vise to the machine swingably about an axis extending transversely to the neutral plane of a workpiece to be secured to the vise, and means for transversely moving and adjusting the axis of the journal relative to said neutral plane.

ROWLAND BENTLEY.
